WEAR-PREVENTING MEANS FOR PUMPS.

Application filed January 30, 1923. Serial No. 615,847.

My invention relates in general to pumps employed for transferring liquids containing the solid materials in suspension, and relates particularly to mud pumps for pumping abrasive materials, such as the mud employed in rotary well drilling operations.

In this disclosure I shall describe my invention as applied to mud pumps employed in the oil fields for pumping lubricating mud mixture into the hole being drilled. This lubricating mud is generally a mixture of clay and water, and therefore contains abrasive materials which cause very rapid wear in the moving parts of the mud pump. It is for this reason that replaceable steel liners are provided in the cylinders so that the pumps may have the efficiency thereof renewed. The wear between the liner and the pump piston is due to the fact that abrasive material adheres to the walls of the liner and passes in between the piston and the liner as the piston reciprocates. This abrasive lubricating mud also adheres to the piston rod and is carried into the packing gland through which the piston rod extends into the pump cylinder. This causes rapid wear upon the piston rod with the result that a frequent renewal is necessary. The valves of such mud pumps are also subject to the rapid wearing action of the mud and must be frequently renewed.

Although I am describing my invention relative to this certain type of pump, it will be readily understood that in various industries, pumps are employed for the purpose of transferring liquids containing solid and abrasive materials, and that my invention is also applicable to these other pumps.

It is the principal object of my invention to provide means in a pump for preventing the material, being pumped, from entering between the moving parts, thereby preventing the rapid wear between these moving parts which is occasioned by such entrance of wear producing materials therebetween. The invention also provides means for clearing the surfaces of the pump valves.

It is a further object of my invention to provide equipment whereby my invention may be employed, which equipment may be attached to and installed in the ordinary type of pumps.

My invention consists essentially of introducing a flow of steam or other fluid between the frictionally engaging surfaces of the

pump, this flow of fluid washing the surfaces and preventing the entrance of abrasive materials therebetween. In application to the piston of the pump, the fluid is forced out between the engaging faces of the piston and the cylinder in a forward direction as the piston moves forwardly, so that the cylinder walls are cleared of abrasive materials ahead of the advancing piston. When the piston advances rearwardly, the clearing fluid is ejected in a rearward direction, thus washing the cylinder walls ahead of the rearwardly advancing piston. When applied to the piston rod, my invention employs a circular channel around the piston rod, this channel being disposed at the inner end of the packing box structure. As the piston rod moves outwardly through the stuffing box, which is in a direction which would ordinarily result in the carrying of abrasive materials into the packing box, a flow of liquid is forced through the annular channel and inwardly along the face of the piston rod, thus washing off the adhering substances from each succeeding portion of the piston rod surface before it passes into the stuffing box. Valve clearing means as shown in the drawing and hereinafter made evident are also provided by the invention.

The especial advantages of my invention and further objects thereof will be made evident hereinafter.

Referring to the drawings which are for illustrative purposes only,

Fig. 1 is a partly sectioned elevation of a mud pump showing the employment of certain features of my invention.

Fig. 2 shows a form of valve structure which may be employed in the practice of my invention with such a pump as shown in Fig. 1.

Fig. 3 is a section taken upon a plane represented by the line 3—3 of Fig. 2.

Fig. 4 is a section taken upon a plane represented by the line 4—4 of Fig. 2.

Fig. 5 is a fragmentary view showing in section a portion of a cylinder equipped with other means for practicing the principles of my invention; the equipment shown in Fig. 5 being preferably employed in high pressure pumps.

Fig. 6 is a section taken upon a plane represented by the line 6—6 of Fig. 5.

Fig. 7 is a partially sectioned plan view of the improved type of balanced valve I

employ with the equipment shown in Fig. 5.

Fig. 8 is a section taken upon a plane represented by the line 8—8 of Fig. 7.

Fig. 9 is a fragmentary sectional view 5 showing a stuffing box equipped with an attachment which adapts the stuffing box to the practice of my invention.

Fig. 10 is a section through the ring member shown in Fig. 9, this section being taken 10 as indicated by the line 10—10 in the Fig. 9.

In Fig. 1, I show a pump having a steam cylinder 15 and a pumping cylinder 16. Through a connecting rod 17, the pump piston 18 is reciprocated by the drive piston 15 15 which operates in the steam cylinder 15. The steam cylinder 15 has steam ports 20 leading into each end thereof, and discharge ports 21 near each end thereof, which are controlled by a slide valve 23 which is operated in the steam chest 24 by a valve rod 25 connected at 26 to the valve lever 27, according to customary practice.

Let it be considered that it is desired to apply my invention to the piston rod 17 and 20 stuffing box 29 of the pump shown in Fig. 1. A steam pipe 30 may be connected between the steam inlet port 20 and an annular recess 31 formed around the piston rod, this interconnection being accomplished through 25 channels 32 and 33 formed respectively in the walls of the steam cylinder and the pumping cylinder. When the valve 23 is in the position shown in the drawing so that the steam port 20 at the right hand end of 30 the cylinder 15 is opened, steam enters between the piston 19 and the right hand head 35 of the cylinder 15 and forces the piston 19, and the connecting rod 17 and piston 18 associated therewith, in a direction indicated 35 by the arrows 36. During this time steam is also being forced through the inter-connecting pipe 30 and the annular channel 31 from which it passes around the piston rod 17 into the cylinder 16. This passage of 40 steam along the face of the piston rod 17 has the effect of removing therefrom any adhering materials with the result that the piston rod is washed clean before it passes into the stuffing box 29; therefore, the entrance of 45 abrasive materials into the stuffing box is prevented and maximum life of the piston rod attained.

For the purpose of applying the invention 50 to the piston and cylinder of the pump, shown in Fig. 1, channels 38 and 39 may be formed longitudinally in the piston rod 17, the channel 38 opening into the steam cylinder 15 at 40 and extending to the rearward end 55 of the piston 18 where it connects into an annular channel 41. The channel 39 is open at 42 to the left hand end of the steam cylinder 15 and extends through the piston rod 17 to the forward end of the pump piston 18 where it connects into an annular 60 channel 43. An annular channel 44 is

formed at the rearward end of the pump piston 18 in the circumferential face thereof, and an annular channel 45 is similarly formed near the forward end of the pump piston 18. Radial passages 46 connect between the channels 41 and 44 and radial passages 47 connect between the channels 43 and 45. When the pistons are moving in the direction of the arrow 36, steam under pressure between the piston and the head 35 of the cylinder 15 is forced through the channel 38 to the annular channel 41 from which it is thence distributed through the passages 46 to the outer channel 44. From this channel 44 it passes, in the same direction as the movement of the pistons, between the face of the piston and the face of the pump liner 48 and washes the face of the liner 48 clear of adhering substances ahead of the advancing piston. When the pump has reached the end of its stroke in the direction of the arrow 36, the slide valve introduces steam between the steam piston 19 and the head 49 of the cylinder 15, whereupon moving the piston in a direction opposite to that indicated by the arrows 36. During this opposite movement, steam under pressure passes through the channel 39, through the channel 43 and passages 47, and is forced from the channel 45 between the face of the piston 18 and the face of the liner 48, in a direction indicated by the arrow 50, thus washing the face of the liner 48 on the opposite side of the piston as it moves in a direction opposite to the arrow 36, or in other words, in the direction indicated by the arrow 50.

In Fig. 2 of the drawing I show a pump valve structure which may be employed with the mud pump shown in Fig. 1. This valve structure provides a seat ring 55 which is inserted in the valve opening 56 provided for this purpose in the division wall 57 of a pump. This member 55 has the upper rim thereof given the V formation shown at 58. A valve closure member 59 is provided having an annular V-shaped channel 60 formed therein which fits down over the valve seat in the manner shown in Fig. 2. The closure member 59 is formed of an outer cup shaped member 60 provided with an annular flange 61 and having an annular groove 62 formed therein. Within this outer member 60 a filler plate 63 having radial channels 64 therein is placed and secured by bolts 66 which hold the upwardly extending shank 67 of the valve closure member 59 against the member 60. The shank 67 is cylindrical in form and extends out through a packing box 69 mounted in the outer wall 70 of the pump and has a concentrically disposed tube 71 mounted therein which has a packing box 72 at the upper end thereof and a lateral outlet 73 to which a flexible steam hose 74 may be connected. Centrally through the tube 71 a valve rod 75 extends. This valve 110

rod has a valve head 76 upon the lower end thereof which is adapted to close an orifice 77 which leads to the radial channels 64 connecting with the annular channel 62. The 5 upper end of the valve rod 75 is connected to a shaft 79 which threads, as indicated at 80, into a block 81 mounted upon the shank 67 by bars 82. This shaft 79 has diametral- 10 ly projecting pins 84 near the upper end thereof which extend into helical channels 85 formed in a stationary block 86 which may be supported by a bracket 87. Steam or other fluid under high pressure is delivered through the hose 74 into the tube 71. 15 When the valve closure member 59 is raised due to the pressure thereagainst, the valve structure which includes the shank 67, the block 81, and the shaft 79 move upwardly. In moving upwardly, the diametrically ex- 20 tending pins 84 must follow the helical channels 85, thereupon rotating the shaft 79 in the block 81. Due to the threaded en- gagement of the shaft 79 with the block 81 as indicated at 80, the shaft and the valve 25 rod 75 attached thereto revolve upwardly relative to the valve structure, with the result that the valve head 76 is raised from the orifice 77 and steam allowed to flow through the channels 67 into the annular 30 channel 62 from whence it is distributed, through passages 89, between the V-shaped faces of the closure member 59 and valve seat 55. When the valve structure again lowers, the shaft 79 rotates in the opposite 35 direction with the result that the orifice 77 is again closed by the valve head 76.

I have previously described my invention in operation with a low pressure type of pump. In such pumps the resisting pressure which must be pumped against is lower than the pressure of the steam employed in the steam cylinder and the drive piston and the pumping piston are made of substantially the same size. In this type of pump, 40 steam from the valve chest may be employed as shown in Fig. 1. In high pressure pumps, however, the pumping piston is constructed considerably smaller than the steam or drive piston, so that an increase in pressure may be obtained thereby. In such pumps the 45 pressure in the pump cylinder is much greater than the pressure of the steam employed for driving the pump; therefore, it becomes necessary to use a fluid, or steam, 50 under high enough pressure to overcome the pressure within the pumping cylinder. In 55 application to high pressure pumps, I employ an arrangement such as shown in Fig. 5.

60 In Fig. 5, 90 represents a steam pipe leading from high pressure boiler into a valve 91 which connects through a pipe 92 with the annular channel 93 formed around the piston rod 94. The valve 91 is constructed 65 as shown in Figs. 7 and 8, in which 95 rep-

resents a body having an inlet passage 96 into which vertical holes 97 are drilled. A revolvable plate 98 operates against the top face of the valve block 95 and has holes 99 therein which cooperate with the holes 97. 70 An outlet channel 100 is drilled into with vertical holes 101, and similar holes 102 are provided in the plate 98, as shown in Fig. 8. Steam enters the cap 104 of the valve 91 through the passages 97, which are disposed 75 equidistant upon either side of the center axis of the valve, and discharges through the holes 101 which are also disposed equidistant from the center of the axis and lie in a plane perpendicular to the plane of the 80 holes 97. The shaft 105 may be rotated upon the face of the block 95 by a lever 106 in such a manner that the holes 99 and 102 are removed from alignment with the holes 97 and 101, as indicated at 107 and 108, thus 85 preventing the flow of steam through the valve.

As shown in Fig. 5, the lever 106 has downwardly extending ends 109 and 110 which may be engaged by a block 112 mounted upon the piston rod 94. When the lever 106 has a right hand end thereof raised as indicated by the full lines 114, the valve is 90 opened and steam is allowed to pass through the channel 93. When the left hand end of the lever 106 is raised as indicated by the dotted lines 115, the valve is closed. In 95 Fig. 5, the valve is shown in open position and the piston rod 94 is moving in the direction of the arrow 116. During the movement of the piston 94 in this direction, steam is flowing through the channel 93 and the piston rod washed thereby. Upon the block 112 striking the lower end of the downwardly extending portion 110 of 100 the lever 106, the left hand end of the lever is raised and the valve closed, so that no steam will flow during the movement of the piston rod in the direction opposite to the arrow 116. It will be perceived that the 105 flow of steam during this movement of the piston rod is unnecessary as the piston rod is moving away from the gland into the interior of the pump cylinder 118. Upon the piston rod 94 reaching the end of its stroke 110 in the direction indicated by the arrow 120, the block 112, as indicated by the dotted lines 12, raises the right hand end of the lever and thus opens the valve 91 just before the piston rod starts on its return 120 stroke. Therefore, a flow of steam around the piston rod 94 is started before the commencement of its movement in the direction of the arrow 16, with the result that there is no possibility of any abrasive substance 125 entering into the packing gland 122.

The piston 125 shown in Fig. 5 is of a special design, and is so constructed that it operates as a valve for controlling the 130 delivery of steam to the channels 126 and

127 in the outer member 128 thereof. This control is accomplished in the following manner: The outer member 128 has a central reduced portion 129 which extends in-
 5 to an annular recess 130 formed in the inner member 132, which recess is slightly longer than the annular projection 129, as shown at 133. This inner member 132 is divided into two portions, 134 and 135, up-
 10 on a line 136 so that it may be assembled within the outer member 128 by inserting the members 134 and 135 from either end of the member 128. It will be perceived that the frictional engagement of the pack-
 15 ing 136 of the pistons with the cylinder wall 137 will have the tendency to move the outer member 128 upon the inner member 132 within the limits of the annular recess 130. In Fig. 5, the member 128 is disposed
 20 in the position which it assumes when the piston is traveling in the direction indicated by the arrow 116. The inner member 132 is, therefore, moved forwardly within the outer member and the radial channel 138
 25 coincides with an annular channel 139 formed in the outer member 128, from which channel the steam is delivered through radial passages 140 to the channel 127 so that the steam may flow in the direction indicated by the arrow 116 between the faces of the piston 125 and the cylinder wall 137. Steam is fed to the piston through a longitudinal channel 142 formed in the piston rod 94. This channel 142 communicates,
 30 through a radial passage 143 and a nipple 144, with a flexible steam hose 145 which in turn has connection with the high pressure steam supply. When the piston reaches the ends of its stroke in the direction indicated by the arrow 116, the reverse stroke indicated by the arrow 120 starts. The first movement within the piston 125 at the start of the reverse stroke is the travel of the inner member 132 within the outer member
 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

To prevent the entrance of the material being pumped between the outer member 128 and the inner member 132, flexible rings 155 are provided which are secured by rings 156 and screws 157 to the ends of the members 128 and 132, as shown. These flexible rings effectually prevent any entrance of abrasive substances into the valve structure of the piston. Channels 160 are also provided for the delivery of steam to the under 75 side of the packing 136 for the purpose of holding the packing tightly against the walls of the cylinder.

In certain types of pumps, as shown in Fig. 9, the packing chamber is enclosed by walls 170 which are cast integrally with the head 71 of the cylinder. For this type of packing chamber I provide a ring member 172 having an inner annular channel 173 and an outer annular channel 174 which are connected by radial passages 176. This ring may be placed in the packing chamber 178 as shown in Fig. 9, and a hole 180 drilled into the wall 170 in a manner to communicate with the outer channel 174. The steam pipe 181 is then threaded into the outer end of the hole 180, as shown, so that steam will be delivered into the outer channel 174, through the passages 176, and into the inner annular channel 173 from whence it is forced, as indicated by the arrows 184, across the face of the connecting rod as previously described, functioning in the same manner as described relative to the channel shown in Figs. 1 and 5.

It is desirable to use steam as a washing fluid in the practice of my invention owing to the fact that upon the steam coming in contact with the cold liquid or mud contained in the pump cylinder, it will immediately condense to a very small fraction of its original volume as steam and will, therefore, when condensed to water, require but little space within the pump cylinder. The invention is particularly adapted to oil pumps used for transferring oil through long pipe lines such as now employed for delivering oil from the oil fields to the transportation points, as this oil carries in suspension a certain amount of sand and other abrasive materials which are very detrimental to the reciprocating parts of the pumps employed for driving it through the lines.

I claim as my invention:

1. A pump organization comprising walls 120 forming a cylinder; a piston operating in said cylinder; walls of said piston being disposed to form an annular channel near each end of and in the cylindrical face of said piston; and means for forcing a fluid through said channels and between the faces of said piston and said cylinder walls, which means is adapted to deliver said fluid alternately through said channels, said delivery being through the channel disposed at the end of said piston 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

concurring with the direction of travel of said piston.

2. A pump organization comprising walls forming a cylinder; a piston operating in said cylinder; walls of said piston being disposed to form an annular channel near each end of and in the cylindrical face of said piston; and means for forcing a fluid through said channels and between the faces of said piston and said cylinder walls, which means includes a valve arrangement in said piston adapted to deliver said fluid alternately to said channels, said delivery being through the channel disposed at the end of said piston concurring with the direction of travel of said piston.
3. In a pump, the combination of: walls forming a cylinder; a head for said cylinder having a packing member therein; a piston rod operating through said packing member; means for preserving a flow of fluid over the surface of said rod at the point of entry of said rod into said packing member, and in a direction opposite to the direction of travel of said rod; a pump piston on said piston rod; means for introducing a flow of washing fluid between the engaging surfaces of said cylinder and said piston in the same direction as said piston is moving;
- valve seats associated with said cylinder; ³⁰ closure members for said valve seats; and means for introducing a flow of washing fluid between the engaging surfaces of said seats and said closure members during the periods said closure members are raised ³⁵ from said seats.
4. In a pump, the combination of: walls forming a cylinder; a head for said cylinder having a packing member therein; a piston rod operating through said packing ⁴⁰ member; means for preserving a flow of fluid over the surface of said rod at the point of entry of said rod into said packing member; a pump piston on said piston rod; means for introducing a flow of washing fluid between the engaging surfaces of said cylinder and said piston; valve seats associated with ⁴⁵ said cylinder; closure members for said valve seats; and means for introducing a flow of washing fluid between the engaging surfaces of said seats and said closure members during the periods said closure members are raised from said seats.

In testimony whereof, I have hereunto set my hand at Taft, California, this 18th ⁵⁵ day of January, 1923.

FRANK J. WISE.
